UNITED STATES PATENT OFFICE.

HARRY D. MORTON, OF NEW YORK, N. Y.

SURGICAL NEEDLE AND METHOD OF MAKING THE SAME.

Application filed September 9, 1925. Serial No. 55,268.

The following is a description of a surgical needle and methods of making the same embodying my invention in the form and manner at present preferred by me; but it will be understood that various modifications and changes may be made without departing from the spirit of my invention and without exceeding the scope of my claims.

In surgical operations much effort is required to force a needle of the usual type through certain tissues, such as the skin upon some portions of the body, the scalp and tendons; and the principal object of my invention is to provide a needle having keen cutting edges, permitting it to be more readily passed through such tissues than any other type of needle with which I am familiar. It will be apparent, however, that my invention also possesses utility in other arts than surgery, where it is necessary to pass a needle through resistant material.

I am aware that it is old in the prior art to employ needles having three or more flat sides. Such needles are open to the objection that the angles formed by such adjacent sides are so obtuse as to preclude the possibility of machining them to a keen cutting edge. For example, such sides on a triangular needle form 60° angles; and, on a square needle 90° angles. Nearly as great pressure is therefore necessary to force such a needle through certain tissues as is required when the ordinary conically-pointed needle is employed. Surgical needles are usually of relatively small diameter; and if it were attempted to hollow grind them in order to produce keen cutting edges, the abrasive wheels would necessarily be of lesser diameters than the tapered portion of the needle itself, and would therefore be very delicate and short-lived. Furthermore, in order to give the high surface speed requisite for properly abrading the metal to form keen cutting edges, it would be necessary to rotate these small wheels at an impracticably high rate. By my invention it is possible, with simple and practical manufacturing methods, to externally grind the needle to form a plurality of edges so keen that only slight effort is required to cause the needle to readily cut its way through thick and resistant tissues.

My invention will best be understood by reference to the accompanying drawings, in which I have illustrated the preferred forms

of my invention and methods of making the same, and in which Fig. 1 shows, partly in section and partly in perspective, a portion of a needle blank with the usual conical point; Fig. 2 is a similar view of a portion of such blank after there have been formed therein three tapered grooves, starting on the straight portion of the needle somewhat above the tapered portion thereof and terminating close to the point of the blank; Fig. 3 shows, partly in section and partly in perspective, such needle blank with one of the three flutes between the grooves externally ground away to form a blade having a keen cutting edge; and also, in perspective, a portion of an abrasive wheel which may be employed for this external grinding; Fig. 4 shows, partly in section and partly in perspective, the point and three cutting blades of the needle in finished form; Fig. 5 is an elevation of a portion of a completed needle with a part thereof broken away to show the form of the groove and blades.

Like reference characters indicate like parts throughout the drawings.

Referring to the drawings: 1 indicates the body of a needle, which may have formed in its shank end an eye or other thread-carrying means (not shown). 2 is the point of the needle, which may be of any convenient shape and which may be formed in the annealed blank by any suitable method, as by grinding or swaging. 3^a, 3^b and 3^c are tapered grooves, the sides of which follow the shape of the tapered portion of the needle blank—such grooves being formed by stamping, pressing or other suitable means, while the blank is in an annealed condition, and either before or after it is pointed. The bottom of each groove is preferably parallel to the axis of the needle blank, so that a strong central core of substantially uniform cross-sectional area extends throughout the grooved portion of the blank; and so that the height from this core of the cutting blades to which the flutes are reduced progressively increases as such blades approach the straight portion of the needle. 4^a, 4^b and 4^c are flutes remaining in the tapered portion of the blank after the pointing and the forming of the grooves 3^a, 3^b and 3^c. In the machining of each flute material is preferably so removed from one side thereof as to leave a cutting edge coincident with the surface of the blank, so that

the cutting edges of all the flutes converge toward the needle point at the same angle as that of the original blank. Before the blank is hardened, a portion of the perimeter of each flute may be removed throughout the length thereof, as by milling or by external rough grinding; or, if preferred, this external grinding may be done at one operation after the blank has been hardened, tempered and polished. After the point, grooves and eye (or other thread-attaching means) have been formed in the needle blank, the blank may be hardened, tempered and polished in the usual manner—the extreme point being re-ground, if necessary. The grooves 3^a, 3^b and 3^c are preferably carried beyond the tapered portion of the blank and for a short distance along the straight portion thereof, in order to provide means for so registering and holding the blank in a fixture (not shown) that the flutes may be brought into contact with an abrasive wheel in the correct position for grinding. The flutes 4^a, 4^b and 4^c are then successively moved into and maintained in contact with the face of an abrasive wheel 5, in such a position and for such a time as to remove sufficient of the remaining material from the perimeter of each such flute as to reduce it to a blade having a keen cutting edge. In the grinding operation, the needle is so supported that the upper edge of the flute which is to form the cutting edge and toward which the grinding is to be done, is parallel to the axis of rotation of the abrasive wheel. The contour of the flutes is such as to permit of feeding the needle at a right angle to the axis of rotation of the abrasive wheel and directly against the face thereof so that the abrasion is effected without the necessity of feeding it across such face—thereby producing a much keener cutting blade than would otherwise be possible. The grinding thus starts at the widest portion of the tapered flute and, as the needle is fed forwardly, the ground surface continues to lengthen until the small end of the flute is reached. This results in reducing each flute to a radial blade which extends the entire length of the tapered portion of the needle except the extreme point thereof.

It will be obvious that the external grinding which is made possible by my construction permits of the use of an abrasive wheel of much larger diameter than that of the needle. This is a very advantageous feature, because it is thereby possible to impart a high surface speed to such wheel, with consequent improvement in the cutting qualities of the blades. The cutting edges may, after grinding, be subjected to a stropping process, such as is well known to those skilled in the art.

What I claim as new and desire to secure by Letters Patent of the United States is:

1. A needle having a plurality of tapered blades extending along a core of substantially uniform cross section.
2. A needle having a plurality of tapered blades radiating from a core of substantially uniform cross section.
3. A surgical needle having a point, a body, a plurality of radial cutting blades extending throughout a portion of the distance from said point to said body and a core of substantially uniform cross section adjacent said blades.
4. A needle having formed therein a plurality of alternate grooves and flutes, the bottom of each such groove being substantially parallel throughout its length to the longitudinal axis of said needle and the said flutes forming cutting blades.
5. A needle having a conical end, a plurality of cutting blades extending along a portion thereof, and a core of substantially uniform cross section adjacent said blades.
6. A needle having formed in a tapered portion thereof a plurality of alternate grooves and flutes, the bottom of each such groove being substantially parallel throughout its length to the longitudinal axis of said needle and the perimeter of each of said flutes being externally ground to form a cutting blade tapering in height toward the point of such needle.
7. The method of making a needle which consists in forming alternate tapered grooves and flutes in a blank and producing a cutting edge on each such flute by machining metal from the perimeter thereof.
8. The method of making a needle which consists in forming three or more tapered grooves in a blank and producing a cutting edge on each of the flutes between said grooves by externally grinding the perimeter thereof.
9. The method of making a needle which consists in conically pointing a blank, grooving a part of said conical portion to form a plurality of flutes, hardening and tempering said blank and machining metal from the perimeter of each such flute to reduce it to a cutting blade.
10. The method of making a cutting needle which consists in forming a plurality of alternate tapered grooves and flutes in a blank, hardening, tempering and pointing said blank, positioning said blank with an edge of each of said flutes successively parallel to the axis of rotation of an abrasive wheel, and machining metal from the perimeter of each of said flutes by feeding the same at a right angle to the axis of rotation of said wheel to reduce such flute to a cutting blade.
11. The method of making a needle which consists in tapering a portion of a blank, grooving said tapered portion through a part of its length to produce a plurality of

flutes and a core of substantially uniform cross section throughout said grooved portion, and forming a cutting edge on each such flute by machining metal from the perimeter thereof.

12. The method of making a needle which consists in conically pointing a blank, grooving a part of said conical portion to pro-

duce a plurality of flutes and a core of substantially uniform cross section throughout said grooved portion and forming a cutting edge on each such flute by grinding metal from the perimeter thereof with an abrasive wheel of substantially greater diameter than the diameter of said blank.

HARRY D. MORTON.
